UNITED STATES PATENT OFFICE.

RICHARD A. JOHNSTON, OF NEW YORK, N. Y., ASSIGNOR TO BARRON G. COLLIER, INC.,
OF NEW YORK, N. Y.

ADVERTISING-CARD HOLDER.

Application filed December 17, 1923. Serial No. 681,205.

To all whom it may concern:

Be it known that I, RICHARD A. JOHNSTON, a citizen of the United States, residing at New York city, in the county of New York, 5 State of New York, have invented certain new and useful Improvements in Advertising-Card Holders, of which the following is a specification.

My invention relates in general to devices 10 for holding advertising cards and more especially to billboards or frames such as are used in displaying advertising cards on street railway cars and the like.

The prime object of my invention is to 15 provide a billboard frame in which advertising posters may be conveniently and positively secured and readily removed for the insertion of other posters.

Another object of my invention is to 20 provide a frame, the parts of which may be inexpensively manufactured and assembled.

Other objects of my invention will appear 25 in the accompanying specification and claims and will be disclosed in the accompanying drawings in which—

Figure 1 is a front elevation of my device;

Figure 2 is a cross section taken on the line 2—2 of Figure 1;

Figure 3 is a cross section taken on the 30 line 3—3 of Figure 1;

Figure 4 is a cross section taken on the line 4—4 of Figure 1.

Referring with greater particularity to the drawings it will be seen that my device 35 is comprised as follows: The main or back portion 1 of the frame is stamped out of sheet metal. In the stamping process it will be noted that the metal is cut and stamped to provide apertures 11, crimped over sides 40 6—6 and base 7, apertures 8, the substantially centrally disposed upstanding crimped flanges 10 and a series of tongues 4 near its upper portion. A top plate 2 also stamped of sheet metal has its upper edge 5 crimped 45 over and is provided with a series of vertically extending slots, corresponding in number and relative positions to the tongues 4. A thin block of wood 9 is adapted to be held in position by the flanges 10. The apertures 50 11 are provided for securing the frame to the vehicle or building. Apertures 8 are provided to drain off rain water.

In assembling my device it is only necessary to fit the tongue of the base plate 1 into the slots 3 of the top plate 2 and then 55 bend tongues over as shown in Figures 1, 2 and 4. The block of wood 10 is then fixed in position under flanges 10—10.

To insert an advertising card it is only necessary to lift upwardly on the top plate 60 2, the tongues 4 riding in slots 3, until the crimped edge is high enough above the edges 6 to permit the insertion of the card between the crimped edges 6—6, 7 and the back plate. The top plate is then shoved 65 downwardly to the position shown in Figure 1 where the crimped over edge 5 will engage the upper end of the card. To prevent the card from bulging in the middle it will then be tacked to the wooden block 9. 70

From the foregoing it will be seen that I have provided a billboard frame, capable of great economy in manufacture and ease of assembly, one which provides for the insertion and removal of cards with the minimum of effort, and one which will prevent distortion of the advertising cards displayed. 75

I claim—

1. In a frame for holding advertising cards, a back plate having crimped over 80 sides and base, and a top plate having a crimped over upper edge, said back plate and said top plate being permanently secured to each other but capable of limited relative motion in one direction, said back plate having substantially centrally disposed upstanding flanges, and a wooden block secured by said flanges.

2. In a frame for holding advertising cards, a back plate having crimped over 90 sides and base, and a top plate having a crimped over upper edge, said back plate and said top plate being permanently secured to each other but capable of limited relative motion in one direction, said back plate having substantially centrally disposed upstanding flanges, a wooden block secured by said flanges, and a plurality of drainage openings in the crimped over edge of the base of said back plate. 95

3. In a frame for holding advertising cards, a back plate having means for holding the outer edges of a card carried thereon, a top plate adjustably carried thereon 100

having card-engaging means on its upper edge, and a wooden block removably secured on said back plate intermediate of its vertical and horizontal edges.

5. In a frame for holding advertising cards, a back plate having means for holding the outer edges of a card carried there-

on, a top plate adjustably carried thereon having card-engaging means on its upper edge, and a wooden block secured on said back plate intermediate of its vertical and horizontal edges.

In testimony whereof I affix my signature.

RICHARD A. JOHNSTON.
